UNITED STATES PATENT OFFICE.

THOMAS G. TURNER, OF NEW YORK, N. Y.

INCANDESCENT-LAMP BASE.

961,326.

Specification of Letters Patent. Patented June 14, 1910.

Application filed October 12, 1908. Serial No. 457,249.

To all whom it may concern:

Be it known that I, THOMAS G. TURNER, a citizen of the United States, residing at New York city, in the borough of Manhattan, county and State of New York, have invented certain new and useful Improvements in Incandescent-Lamp Bases, of which the following is a clear, full, and exact description.

- 10 The object of this invention is to provide means adapted to render useless incandescent electric lamps when removed from a socket after having been once inserted therein.
- 15 The mechanical means for accomplishing this invention may of course be varied to any extent which experience and expediency may require.

In the following specification and in the drawings accompanying the same I have shown certain constructions adapted to secure the result desired.

In essence, my invention consists of a lamp base and lamp adapted to enter any ordinary screw shell socket, as would any standard lamp, but provided with means so that upon the attempt to remove the lamp, the connections between the filament and the terminal to the base will be broken, and destroyed, so as to render the lamp useless.

The scope of my invention will be pointed out in the claims.

In the accompanying drawings, Figure 1 represents my improved lamp in side elevation with the socket shell in section. Fig. 2 is a sectional view of a portion of the lamp of Fig. 1 on line 2—2 thereof. Fig. 3 is a side elevation of the inner member of the base and a portion of the bulb. Fig. 4 is an enlarged sectional plan on line 4—4 of Fig. 2. Fig. 5 is a side elevation partly broken away of a modified form of base. Fig. 6 is a side elevation of the base of Fig. 5 in place in a socket. Fig. 7 is an enlarged section on line 7—7 Fig. 6 and Fig. 8 is an enlarged detail on line 8—8, Figs. 6 and 7.

As shown in the drawings, 1 is the lamp bulb, 2 is an ordinary filament sealed in the neck of the bulb, 3 and 4 are connecting wires. The wire 3 leads from the filament to the end or button terminal 5 of the lamp, the wire 4 leads to the screw shell terminal 6 passing through an insulating disk 7 secured to and forming a part of the inner member hereafter described. The terminals 5 and 6

are secured to each other by the ordinary insulating disk 8, which taken as a whole, constitute the outer member. I prefer to place a kink 9 in the wire 4 to aid in its rupture at the proper time. The inner member is secured to the bulb by plaster-of-paris or other cementing means 10, and it consists of the insulating disk 7, and a shell member 11, threaded internally into the outer shell terminal 6. Normally the inner shell member 11 fits snugly against the top of the outer shell so as not to be capable of being further rotated or binding on its thread when the lamp is turned clockwise, during its insertion into the socket shell. The outer member 6 is formed with an indented lug 12 which is free to slide in a recess 13 of the inner shell. In normal position the lug occupies the position shown in Fig. 4. Upon inserting the lamp and rotating the bulb clockwise the lug 12 will abut against the end of the groove 13, so that all parts will turn as an entirety. On attempting to remove the lamp however, the shell 6 will bind more or less, as it is made a snug fit to hinder its ready removal, and the bulb and inner member will be rotated independently throughout the length of the slot 13 causing the disk 7 to draw taut the wire 4 and break the same, thus placing the lamp out of commission. It will be seen that the kink 9 in the wire will aid in locating the place of breakage. At the same time a factory equipped to repair lamps, by removing the base, can readily repair the lamp.

In Figs. 5 to 8, I have shown a modified form of lamp, differing essentially in that I supply a positive means for hindering the removal of the outer shell to insure a breakage of the connecting wire instead of relying on frictional grip alone by the outer shell on the socket. In the modification 14 is the socket shell. The inner shell 15 is formed with a flared out skirt 16 fitting the socket shell 14 but of lesser diameter above the skirt 16. On the reduced diameter of the inner shell there is mounted an outer shell 16' carrying a spiral spring 17 of one or more turns, as may be desired. A lug 18 of the inner shell is turned outwardly and upwardly to slide in a groove 19 in the spring 17. A lug 20 on the outer shell in the normal position of Fig. 7 may act as a stop for the lug 18. The conducting wires 21 and 22 and disks 23 and 24 may be like those of Figs. 1 to 4.

In operation upon inserting a lamp the inner shell and bulb will rotate together causing the lug 18 to bear upon the lug 20 and rotate the outer shell. This leaves the 5 spring 17 free to follow into place without binding. Upon removal, however, the bulb and inner shell will travel together, the outer shell will positively bind due to the clutch action of the spring 17 and the conductor 21 will be broken. The continued 10 motion of the bulb will however cause the lug to bear upon the end of the groove or recess 19 in the spring 17, relieve the spring from its clutch function and permit the removal of the lamp after the breaking of its 15 connecting wire.

I claim as my invention:

1. An electric bulb, a filament, end and screw shell terminals, connecting wires leading 20 from said terminals to the filament, and means for destroying the connection between one of said terminals and the filament to render said lamp useless, adapted to come into operation upon and by the removal of the 25 lamp from its socket.

2. An electric lamp comprising a bulb, a filament, end and screw shell terminals, connecting wires leading from said terminals to the filament, and means adapted to break the 30 connecting wires, operable upon and by the removal of the lamp from its socket.

3. An electric lamp comprising a bulb, a filament, end and screw shell terminals, connecting wires leading from said terminals to the filament, means adapted to break the 35 connecting wires, operable upon and by the removal of the lamp from its socket, and means for hindering the removal of the lamp from its socket.

4. An electric lamp comprising a bulb, a filament, end and screw shell terminals, connecting wires leading from said terminals to the filament, said screw shell comprising 40 two parts immovable with relation to one another during the insertion of the lamp in its socket, means to permit movement of the part secured to the bulb independently of the other shell, upon rotating the lamp, in the direction of its removal, the connections 45 adapted to be destroyed between the terminals and filament upon such independent motion.

5. An electric lamp comprising a bulb, a filament, end and screw shell terminals, 50 connecting wires leading from said terminals to the filament, said screw shell comprising two parts immovable with relation to one another during the insertion of the lamp in its socket, means to permit movement of the part secured to the bulb independently of the other shell upon rotating the lamp in the 55 direction of its removal, and means for hindering the removal of the said other shell.

6. An electric lamp comprising a bulb, 60 a filament, end and screw shell terminals,

connecting wires leading from said terminals to the filament, said screw shell comprising an inner and an outer member, the inner member secured to the bulb, the outer member adapted to contact with a socket shell, 70 two of the connecting wires passing through the inner member, said members being rotatable with relation to each other and means to prevent their rotation upon the insertion of the lamp into its socket. 75

7. An electric lamp comprising a bulb, a filament, end and screw shell terminals, connecting wires leading from said terminals to the filament, said screw shell comprising an inner and an outer member, the inner 80 member secured to the bulb, the outer member adapted to contact with a socket shell, two of the connecting wires passing through the inner member, said members being rotatable with relation to each other, means to prevent their rotation upon the insertion of the lamp into its socket, and means for hindering the removal by rotation of the outer shell.

8. An electric lamp comprising a bulb, 90 a filament, end and screw shell terminals, connecting wires leading from said terminals to the filament, said screw shell comprising an inner and an outer member, the inner member secured to the bulb, the outer member 95 adapted to contact with a socket shell, two of the connecting wires passing through the inner member, said members being rotatable with relation to each other, means to prevent their rotation upon the insertion of the lamp into its socket, said means consisting of a recess in the periphery of one shell and a lug carried by the other shell entering the recess.

9. An electric lamp comprising a bulb, 105 a filament therein, end and screw shell terminals, connecting wires leading from the terminals to the filament, one of said terminals being movable with relation to the bulb and hindered from motion by said connecting wire. 110

10. An electric lamp comprising a bulb, a filament therein, end and screw shell terminals, connecting wires leading from the terminals to the filament, one of said terminals being movable with relation to the bulb and hindered from motion by said connecting wire, and means for increasing the grip on the socket by the terminal which is movable with relation to the bulb. 115

11. An electric lamp comprising a bulb, a filament therein, end and screw shell terminals, connecting wires leading from the terminals to the filament, one of said terminals being movable with relation to the bulb and hindered from motion by said connecting wire, a stop limiting the extent of movement of the movable terminal. 125

12. An electric lamp comprising a bulb, a filament therein, unbroken connecting 130

wires leading from the filament, a member secured to the lamp but movable relatively thereto, said member being operatively connected with a connecting wire whereby upon
5 a movement of the member relatively to the bulb the connecting wire will be rendered inoperative.

Signed at New York city this 9th day of October 1908.
